UNITED STATES PATENT OFFICE.

MORRIS EPSTEIN, OF NEW YORK, N. Y.

DESIGN FOR A CIGAR-CASE.

SPECIFICATION forming part of Design No. 28,176, dated January 18, 1898.

Application filed March 2, 1897. Serial No. 625,801. Term of patent 3½ years.

To all whom it may concern:

Be it known that I, MORRIS EPSTEIN, a citizen of the United States, residing at New York, in the county of New York and State of New York, have invented and produced a new and original Design for Cigar-Cases, of which the following is a specification, reference being had to the accompanying drawings, showing a part thereof.

- Figure 1 is a plan view of a cigar-case, showing my new design. Fig. 2 is a sectional view taken on line X X of Fig. 1.

As shown in the drawings, the leading or material feature of my design consists of the cigar-shaped protuberance A, arranged as shown in Fig. 1, the said protuberance being concavo-convex, as shown in Fig. 2, and the beaded edges D around the top and side edges of the case. The plate E, at the top of

the case, has its upper edge F formed of compound curves in its length and a boss G in its reentrant angle, as shown. In the spaces between the protuberances A are branches a, with oak-leaves and acorns on them.

It is apparent that this design is applicable to cigarette-cases and like articles.

Having described my invention, what I claim as new, and desire to secure by Letters Patent, is—

The design for a cigar-case, as herein described and shown.

In testimony that I claim the invention above set forth I affix my signature in presence of two witnesses.

MORRIS EPSTEIN.
